CLAIM

The ornamental design for a rescue and ice fishing boat, as shown and described.

DESCRIPTION

FIG. 1 is a top, side perspective view of a rescue and ice fishing boat showing my new design;

FIG. 2 is a top, rear perspective view thereof, with a hold-on support member included;

FIG. 3 is a top, front perspective view thereof;

FIG. 4 is a bottom perspective view thereof;

FIG. 5 is a top, rear perspective view thereof, with a partial center platform included; and

FIG. 6 is a top, rear perspective view thereof, with a full center platform included.

The oar locks have been omitted in FIG. 1 for clarity of illustration.
